UNITED STATES PATENT OFFICE

154,571

DESIGN FOR A FONT OF TYPE

David Soshensky, New York, N. Y.

Application June 2, 1947, Serial No. 139,412

Term of patent 14 years

(CL. D64—12)

To all whom it may concern:

Be it known that I, David Soshensky, a citizen of the United States, residing in the city of New York in the county of New York and State of New York, have invented a new, original, and ornamental Design for a Font of Type, of which the following is a specification, reference being had to the accompanying drawings, forming part thereof.

Figures 1, 2, 3, 4, 5, 6, 7, 8, 9, 10, 11 and 12 are face views on a greatly enlarged scale of a font of type showing my new design.

I claim:

The ornamental design for a font of type, as shown.

DAVID SOSHENSKY.
